US00D837612S

(12) **United States Design Patent** (10) Patent No.: **US D837,612 S**
Shuntich (45) Date of Patent: ** **Jan. 8, 2019**

(54) **SUPERCOOLED BEVERAGE CRYSTALLIZATION SLUSH DEVICE WITH ILLUMINATION**

(71) Applicant: **Supercooler Technologies, Inc.**, Maitland, FL (US)

(72) Inventor: **Douglas Shuntich**, Maitland, FL (US)

(73) Assignee: **Supercooler Technologies, Inc.**, Maitland, FL (US)

(**) Term: **15 Years**

(21) Appl. No.: **29/593,780**

(22) Filed: **Feb. 13, 2017**

Related U.S. Application Data

(62) Division of application No. 29/528,365, filed on May 28, 2015, now Pat. No. Des. 778,687.

CLAIM

The ornamental design for a supercooled beverage crystallization slush device with illumination, as shown and described.

DESCRIPTION

FIG. 1 is an upper front right perspective view of a supercooled beverage crystallization slush device with illumination showing my new design;

FIG. 2 is an upper front left perspective view thereof;

FIG. 3 is an upper rear right perspective view thereof;

FIG. 4 is an upper rear left perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof; and,

FIG. 10 is a bottom plan view thereof.

1 Claim, 10 Drawing Sheets
